WILLIAM HARRISON CORBETT, OF PORTLAND, OREGON.

LOGGING-ENGINE.

No. 840,914.

Specification of Letters Patent

Patented Jan. 8, 1907.

Application filed March 22, 1906. Serial No. 307,340.

To all whom it may concern:

Be it known that I, WILLIAM HARRISON CORBETT, of Portland, Multnomah county, Oregon, have invented certain new and useful Improvements in Logging-Engines, of which the following is a specification.

In logging-engines as usually constructed two winding-drums are employed, one for the main or hauling cable and the other for the trip-line, which is attached at one end to the hauling-cable for the purpose of dragging it back into the woods after a log has been hauled to the engine. The main drum, or the one on which the working cable is wound, should have great power and be operated at a comparatively slow speed, while the auxiliary or trip line drum, having no other function than that of dragging the hauling-cable back into the woods, has less power, but should be capable of high speed to insure the quick return of the hauling-cable and facilitate the drawing in of the logs. It is undesirable in obtaining the desired ratio of speed between the main and trip line to use a very large gear on the main drum or a drum with a small barrel on account of undue wear of the cable, and it is difficult to gear up the auxiliary drum to the desired speed for hauling out the trip-line and still provide a drum of sufficient capacity to take care of the trip-line, which obviously must be double the length of the hauling-cable.

For the purpose of obtaining the desired ratio of speed between the two drums without increasing their diameter to an objectionable degree various systems of compound gearing have been devised, which have generally been effective as far as regulating the speed of the drums is concerned, but have been objectionable on account of the drums operating in opposite directions and coiling at least one of the cables from the underside—a method which in an apparatus of this kind is very undesirable, as it necessitates the raising of the drum in the frame, causing a tendency toward structural weakness, and in case of a slack line allows the cable to drag on other parts of the machine. The "gipsy" head or winch employed for supplementary work should be mounted to overwind its comparatively small cable and be operated rapidly. The overwinding of the line has been obtained by mounting the winch on the shaft of the main drum; but the speed of this shaft is too slow for the work of the winch and has an excess of power.

The objects, therefore, of my invention are to provide a logging-engine having main and auxiliary drums between which the desired ratio of speed is obtained without running into very large diameters.

A further object is to provide drums operating in the same direction and permitting their cables to be wound over instead of under them and the gipsy-winches to be located on the high-speed-drum shaft.

A further object is to place the drums as low as possible in the frame, making the application of all strains direct and overcoming the objectionable features of the ordinary method of compound gearing without increasing the cost of construction.

The invention consists generally in various constructions and combinations, all as hereinafter described, and particularly pointed out in the claims.

In the accompanying drawings, forming part of this specification, Figure 1 is a plan view of a logging-engine, the main and auxiliary drums embodying my invention being illustrated in horizontal section. Fig. 2 is a sectional view on the line *xx* of Fig. 1, and Fig. 3 is a side elevation.

In the drawings, 2 represents a suitable base or frame whereon a shaft 3 is journaled and operated from the engines 4 in the usual manner. 5 is a pinion keyed on the shaft 3 and meshing with a gear 6, secured on a shaft 7, having bearings 8 on one side of said frame and on a bar 9, extending lengthwise of said frame, near the middle thereof. A clutch-shoe 10 of suitable material, such as wood, is secured to the gear 6 and has a wedge-shaped face to enter a socket 11, formed on the head 12 of a drum 13, which is loosely mounted on said shaft 7 and is adapted to slide into engagement with said clutch-shoe, but normally is held out of contact therewith by a spring 14, coiled about the said shaft between a box 15 and the hub 16 of gear 6 thereon. A flange 18 is provided on the head 17 at the opposite end of the drum to receive a brake-strap 19, connected with a shaft 20, that is rocked by a treadle 21, located within convenient reach of the operator. The drum is moved lengthwise on the shaft to lock the friction-clutch by rotating a loosely-mounted toothed sleeve 19' in engagement with a fixed toothed ring 20', said sleeve being operated by a lever 21' or other suitable means. The drum 13 is designed for winding up the trip-line and hauling the main drum-cable back

into the woods after a log has been drawn in. The drum having direct gearing with the crank-shaft will operate at a high speed, and the hauling in of the logs will be thereby greatly facilitated. One end of the shaft 7 projects beyond the frame of the machine, and a winch 22, generally called a "gipsy," is mounted thereon and equipped with a light line (not shown) for doing supplementary work around the engine. This head should revolve rapidly, and its line should be overwound thereon, and by mounting it on the shaft of the high-speed drum I am able to accomplish both objects. Upon the forward end of the bar 9 from the high-speed or trip-line drum I provide a shaft 23, journaled in bearings on said bar and on the opposite side of the frame and carrying an internal gear-ring 24, secured thereon. The shaft 7 extends within this gear and is provided with a pinion 25, meshing therewith and through which and said internal gear the shaft 23 is driven at a slower speed than the shaft 7, the proper ratio being obtained in the well-known way. A clutch-shoe 26 is mounted on said gear-ring, and a drum 27, loosely mounted on the shaft 23, has a head 28, provided with a tapered flange 29 to engage the corresponding surface of the clutch-shoe, being held normally out of contact therewith by a spring 14^a and box 15^a, corresponding to the parts described with reference to the drum 13. The other head 30 of the drum 27 has a flange 18^a for a brake-shoe 19^a, corresponding to the one described and operated by a shaft 20^a and treadle 21^a in substantially the same manner as the brake of the other drum. The drum 27 is moved lengthwise to lock it on the internal gear by any suitable mechanism, as a toothed ring 31, secured on the frame and engaged by a similar ring 32, loosely mounted on the shaft and contacting with a pin 33, slideable in a hole in said shaft and having a bar 34 at its inner end in engagement with a collar 35, contacting with the hub of said drum. The ring 32 is rotated by any suitable means, as the lever 36, and when operated the drum 27 will be moved toward the internal gear and locked thereon. This drum 27 I designate as the "main" or "cable-hauling" drum and is provided with a suitable cable overwound thereon and by means of which the logs are dragged into the engine. The drum operates at a comparatively slow speed; but its barrel is of greater diameter than the drum 13, and it has great power, both characteristics being essential in a drum of this kind.

Both of the drums are set down low in the frame of the machine, thereby avoiding all structural weakness and operating in the same direction, permitting both cables to be wound over instead of under them. The drums being located near together and on substantially the same level will permit of a

compact and durable construction, and each drum will have all the characteristics required, according to the work to be performed by it. The main drum operating the hauling-in cable will have great power and 70 comparatively slow speed, while the trip-line drum, being used merely for pulling the hauling-cable back into the woods, will have less power, but a high speed, and the gipsy-head, being used for light work around the engine, 75 will have practically the same characteristics as the high-speed drum on whose shaft it is mounted.

I do not wish in this application to be confined to the particular means shown and described for moving the drums on their shafts into engagement with the friction-shoes, and the various mechanical devices and improvements thereover may be devised without altering the character of my invention. 80 85

I claim as my invention—

1. The combination, with a driving-shaft, of a drum-shaft geared to said driving-shaft, a closely-mounted drum on said drum-shaft, means for temporarily locking said drum to 90 its shaft, a second drum-shaft, gear mounted thereon, a pinion provided on said first-named drum-shaft and meshing with said gear, whereby said gear will be driven at a slower speed than said first-named drum, a 95 second drum mounted on said second-named drum-shaft, and means for temporarily locking said second-named drum to said gear, substantially as described.

2. The combination, with a driving-shaft, 100 of a drum-shaft geared thereto, a pinion mounted on said drum-shaft, a second drum-shaft, gear mounted thereon, and meshing with said pinion, drums loosely mounted on said shafts, and means for temporarily locking 105 them thereon, substantially as described.

3. The combination, with a driving-shaft, 110 of a high-speed-drum shaft geared thereto, a low-speed-drum shaft having gear connection with said high-speed shaft, and drums 115 mounted on said shafts, operating in the same direction the drum on said high-speed shaft being of less diameter than the drum on said low-speed shaft, substantially as described.

4. The combination, with a driving-shaft, 115 of a high-speed shaft geared thereto, a head provided on the outer end of said high-speed shaft, a pinion mounted on the opposite end of said high-speed shaft, a low-speed shaft, gear mounted thereon and meshing with said pinion, drums loosely mounted on said high and low speed shafts, and means for temporarily locking said drums on said shafts, substantially as described.

5. An engine comprising in combination, a 125 frame, a driven shaft mounted thereon, a pinion secured on said shaft, a high-speed shaft journaled in said frame, a gear secured on said shaft and meshing with said pinion, a pinion provided on one end of said high-speed 130

shaft, a low-speed shaft also journaled in said frame, an internal gear mounted on said low-speed shaft and meshing with said last-named pinion, whereby said shafts will be driven in the same direction, winding drums loosely mounted on said shafts, whereon a trip-line and a hauling-in cable are wound, and means for temporarily locking said drums on said shafts, substantially as described.

6. The combination, with a driving-shaft, of a drum-shaft geared to said driving-shaft, a loosely-mounted drum on said drum-shaft, means for temporarily locking said drum to its shaft, a second drum-shaft, an internal

gear mounted thereon, a pinion provided on said first-named drum-shaft and meshing with said internal gear, whereby said internal gear will be driven at a slower speed than said first-named drum, a second drum mounted on said second-named drum-shaft, and means for temporarily locking said second-named drum to said internal gear, substantially as described.

7. The combination, with a driving-shaft, of a drum-shaft geared thereto, a pinion mounted on said drum-shaft, a second drum-shaft, an internal ring-gear mounted thereon, and meshing with said pinion, drums loosely mounted on said shafts, and means for temporarily locking them thereon, substantially as described.

8. The combination, with a driving-shaft, of a high-speed-drum shaft geared thereto, a

low-speed-drum shaft having an internal gear connection with said high-speed shaft, 35 and drums mounted on said shafts, and operating in the same direction, the drum on said high-speed shaft being of less diameter than the drum on said low-speed shaft, substantially as described.

9. The combination, in an engine of the class described, with a driving-shaft of a direct-geared trip-drum, a compound - geared main drum and a supplementary gipsy-winch, and means for causing said drums and winch to revolve in the same direction, substantially as described.

10. The combination, in an engine of the class described, with a driving-shaft, of a direct-geared trip-drum, a compound-geared 50 main drum, and means for causing said drums to revolve in the same direction.

11. The combination, in an engine of the class described, with a driving-shaft, of a direct-geared, high-speed trip-drum, a compound-geared low-speed main drum, overwound cables for said drums and means for causing said drums to revolve in the same direction, substantially as described.

In witness whereof I have hereunto set my hand this 10th day of March, 1906.
